MINE EXPLODER

Brooks Walker, Piedmont, Calif.

Application May 26, 1945, Serial No. 596,071

2 Claims. (Cl. 89—1)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention pertains to a novel mine exploder for use in military operations in which terrain evacuated by the enemy is suspected of being mined. The invention resides in the class of mine exploders propelled by a powerful vehicle such as a combat tank.

Many of these devices depend on the sheer weight of the parts for functioning the mines. The required weight for successful operation is at all times an impediment and is often in excess of the load that can be propelled by the available vehicles. Another type of mine exploder, known as the beater type, throws a number of chains or flails rotatably against the ground. The objections to this type are the dust raised thereby, the erratic action of the chains, and the liability that mines buried close to the surface will be thrown and exploded against the vehicle or other nearby equipment.

The object of the present invention is to provide a comparatively simple and light-weight apparatus operating by forced impact against the ground, as distinguished from weight alone, and free of the objections to the beater type. Apparatus for these purposes may comprise a number of arms mounted across the vehicle on a horizontal axis and having their forward portions bent downwardly to engage the ground. A suitable trip mechanism may operate on each of the arms in a manner to lift them from the ground and then release them so that they may come into engagement with the ground. A suitable pressure device, such as a spring, may operate on each arm to throw its forward portion against the ground when released by the trip mechanism, the impact being the sum of the net weight of the arm and the force produced by this means. The arms are preferably resilient in order to pass over obstacles without breaking and to accommodate themselves to irregularities on the surface and in the hardness of the ground.

An illustrative embodiment of the invention is disclosed in the following description and in the accompanying drawing in which:

Figure 1 is a side elevation of a military vehicle equipped with the invention;

Figure 2 is a plan view thereof;

Figure 3 is a detailed longitudinal vertical section on line 3—3 of Figure 2, and

Figures 4 and 5 are detail views illustrating modifications of features of construction.

2

In Figure 1 is shown a military vehicle 1 such as a combat tank of the track-laying type. In the body of the vehicle, at its forward end, is journaled a shaft 2 which may be the sprocket 5 shaft for the endless track 3. As is well known, a separate shaft 2 is mounted at each side of the vehicle, the two being capable of independent rotation, and such vehicles are commonly steered by stopping or slowing the transmission to the 10 track at one side while the other is operated at a greater speed, to cause turning of the vehicle. On this shaft is mounted at each side of the vehicle a gear 4 for actuating the novel mechanism of this invention, as will presently be shown. Preferably, at each side of the vehicle an over-running clutch 21 is interposed between each of the gears 4 and shaft 2 for transmitting power from this shaft which produces forward motion of the vehicle. This facilitates turning of 15 the vehicle and provides for operating the mine exploding means only during advancing or forward movements of the vehicle, as well as insuring that a mechanism to be described, driven commonly by the gears 4, will be operated by 20 shaft 2 which has the greatest angular motion.

In the forward end of the vehicle is provided a suitable frame and housing structure 5 for supporting a cam shaft 6 and an intermediate 30 shaft 7. The shaft 7 carries an intermediate gear 8 meshing with the gear 4 and also with a gear 9 on the shaft 6.

The structure 5 supports a series of tamping arms, as will presently be shown, and a suitable 35 support for this purpose may consist of a series of sleeves 10 pivotally mounted on the structure 5 on a horizontal axis at 11. The rear end of each sleeve is in the form of a stem 12 and is adapted to be drawn upward by a spring 13 connecting it to an upper fixed point 14 of the structure 5. The cam shaft 6 carries a series of cams 15 corresponding to and respectively engaging the stems 12.

In each sleeve 10 is inserted and fixed one 45 end of a spring arm 16 consisting preferably of spring steel having a round, square, hexagon or other suitable cross section. Each arm has its forward portion 17 bent downwardly at a substantial angle approximating a right angle. The 50 free end 18 of each arm is positioned to come into engagement with the ground at times and is suitably shaped for that purpose. As one cam 15 proceeds from the position shown in Figure 3, the portion 18 is elevated from the ground by the 55 increasing radius of the cam until the stem 12

trips or drops at the step 19 of the cam. At this time the spring 13, acting upon the stem 12 augments the force of gravity in accelerating the downward motion of the cam 16 and brings the point 18 forcibly against the ground.

As an example of suitable dimensions, each spring arm may have a diameter of one to one-and-a-half inches, and the ground contact point 18 may be about 6 feet in front of the vehicle. The arms should be of such resiliency that the forward portions 17 are permitted to bend rearward on engaging the more common obstacles and thus pass over them. The resiliency may be increased, or brought to the desired degree, by reducing the cross section of the arm at the bend. The mechanism is preferably designed so that one tamp per arm for one rotation of the cam shaft 6 is obtained for each five inches of forward progress. This desirable objective may be and preferably is attained by a proper ratio in the gear train from the shaft 2, or by having steps 19 of the cams 15 displaced angularly with respect to each other in proper degree. Driving power required at any one time is minimized by having the steps 19 of successive cams 15 on shaft 6 circumferentially spaced progressively in substantially like increments so as to trip the arms of the series successively in progression transversely of the vehicle as shown in Figure 4. The spacing of the arms should be about 6 inches center to center or 5 inches edge to edge. On this basis, the ground is struck by the arms at 5 inch intervals lengthwise and transversely of the path. Every mine 20 having a diameter or diagonal of 5 inches or more will be functioned, and it has been determined that practically all enemy mines are within this dimension.

The described actuating mechanism is merely illustrative, and it will be evident that various types of cams and spring tripped toggles, ratchets, pneumatic or hydraulic lifts and drives may be used. The important characteristic of the actuating mechanism is that the arms, when released, will be forced against the ground at a speed greater than that resulting from the mere weight of the arm. By such accelerating means the impact for a given weight is considerably greater than the impact by gravity alone, with the result that the total weight of the apparatus may be correspondingly reduced for a given desired impact.

The several arms 16 need not operate in unison in engaging the ground. It is preferred that the steps 19 of the cams 15 be spaced from one another in a cylindrical surface around the shaft 6, or along a spiral, so that the arms will be operated at regular intervals with respect to each other and thereby make the driving load more nearly constant.

When the vehicle is traveling in territory which is not mined, it is desirable that arms 16 be elevated above the ground and held in inoperative positions. For this purpose, each of sleeves 16 may have associated therewith a lever 22 mounted to pivot at 23 on the structure 5. Each of these levers may have its lower end curved forwardly for engagement beneath a lug 24 carried by each of sleeves 16. If desired, each of levers 22 may have secured to its upper end a cable 26 which may extend rearwardly preferably within the vehicle where it may be secured for holding arms 16 elevated in the position shown in dotted lines in Figure 3.

In Figure 4 there is shown a modification of the pivotal mounting for the spring arms. In

this form a bracket is provided in the form of a split cylinder 27 having opposed mating flanges, one of which is indicated at 28. This bracket is adapted to be clamped in a fixed position about stem 12 by suitable attaching elements such as rivets 29. On the upper side of cylinder 27 there is provided a radial bearing 30 which receives shaft 11 and thus provides a pivotal support. The spring 13 is suitably attached to a bracket 25, fixed to stem 12, to add to the impact force of tamping arm or stem 12.

In Figure 5 an alternate design is shown wherein the end of the tamping arm 16' is anchored rigidly to a clamp 31 which may be rigidly attached to the vehicle or adjusted as shown by hand crank 32, screw 33, nut 34 and ball mounting 35. A connecting rod 36 engages cam 37 at its upper end and is pivoted to arm 16' at its lower end. A contractile spring 38 is connected between rod 36 and any suitable fixed point, as structure 5. In this way, arm 16' is flexed in tamping about bracket 31.

What I claim is:

1. In combination with a vehicle having a driven tractive member at each side, mine exploder apparatus comprising a series of resilient tamping arms extending forwardly from the front of said vehicle and spaced transversely across the latter, each of said arms being pivotally supported at its rearward portion on a horizontal axis by said front of said vehicle for vertical pivotal movement, each of said arms having a forward portion bent downwardly at a substantial angle to the remainder of the respective arm, said forward portion terminating in a downwardly extending free end engageable in a lowered position with the ground and simultaneously yieldable rearwardly on forward progression of the vehicle, means to accelerate downward movement of said forward portion of each of said arms when released from an elevated position in said vertical pivotal movement, and mechanism operably providing said vertical pivotal movement of said arms, said mechanism including a rotatable cam engaging said rearward portion of each of said arms to alternately lift said forward portion thereof to said elevated position and release it therefrom, whereby upon said release said downwardly extending free end will impact the ground with mine detonating force, and operating means connecting said cam with said driven tractive member at each side of said vehicle.

2. In combination with a vehicle having a driven tractive member at each side, mine exploder apparatus comprising a series of resilient tamping arms extending forwardly from the front of said vehicle and spaced transversely across the latter, each of said arms being pivotally supported at its rearward portion on a horizontal axis by said front of said vehicle for vertical pivotal movement, each of said forwardly extending arms having a forward portion bent downwardly at a substantial angle approximately a right angle to the remainder of the respective arm, said forward portion terminating in a downwardly extending free end engageable in a lowered position with the ground and simultaneously resiliently yieldable rearwardly on forward progression of the vehicle, means to accelerate downward movement of said forward portion of each of said arms when released from an elevated position in said vertical pivotal movement, whereby said downwardly extending free end will impact the ground with mine detonating force, mechanism including rotatable cam mem-

bers supported at the front of said vehicle and cooperable with said arms to provide said pivotal movement of the latter, said cam members having steps respectively angularly displaced regularly whereby said downwardly extending free ends are lifted to said elevated position and released therefrom at regular intervals relative to each other, and operating means for said mechanism including an overrunning clutch connection thereto with said driven tractive member on each side of said vehicle.
